UNITED STATES PATENT OFFICE.

OTTO H. ESCHHOLZ, OF WILKINSBURG, PENNSYLVANIA, ASSIGNOR TO WESTINGHOUSE ELECTRIC & MANUFACTURING COMPANY, A CORPORATION OF PENNSYLVANIA.

ARC-SUPPRESSING DEVICE.

Application filed November 29, 1920. Serial No. 427,061.

My invention relates to circuit-interrupting systems and it has for one of its objects to reduce the arcing normally attending the opening of a circuit interrupter.

Another object of my invention is to provide a circuit-interrupting system that shall comprise an electric valve of such characteristics and so related to the interrupter as to shunt the circuit current around the interrupter when the latter is opened and to automatically build up resistance to the current until the flow of the latter is stopped.

In practicing my invention, I provide an electric valve, preferably of the so-called hot-cathode type, of which the cathode circuit is connected in shunt to the circuit and in which the anode circuit, taken in conjunction with the cathode circuit, forms a local series-parallel system connected in shunt to an interrupter. When the interrupter is opened, in response to short-circuit or predetermined overload conditions, the main circuit current is shunted through the anode circuit and there will be substantially no arcing at the interrupter contact members. The arrangement is such that, after the opening of the interrupter and when the main-circuit current is passing through the valve, a rapid diminution of the excitation of the cathode will cool the latter to a temperature below that necessary for electron emission. The valve will, thus, function to rapidly, and by graduated amounts, insert resistance from a valve substantially equal to the resistance of the circuit to be interrupted to infinite resistance preventing the passage of current.

Figure 1 of the accompanying drawings is a diagrammatic view of a circuit-interrupting system embodying my invention and

Figs. 2, 3 and 4 are similar views of modified forms thereof.

In all of the figures, a main circuit interrupter 1, connected to a suitable supply line or main circuit 2, may comprise stationary contact members 3, a main movable bridging contact member 4, an actuating toggle mechanism 5, a stop member 6 for the toggle mechanism, an operating handle 7, and an electromagnetic trip device 8 comprising a movable core member 9, a trip coil 10, connected in circuit with the line 2,

and a resetting spring 11 for the core member 9.

As shown in Fig. 1, an electric valve 12 comprises a cathode 13 that is connected, at one side through an adjustable resistor 14 and a reactor 15, to the main circuit 2 and, at the other side, through a conductor 16, also to the main circuit 2 but with a device 17, that may be a resistor or a reactor, in the circuit 2 between the cathode terminals. The anode 18 of the valve 12 is connected, by a conductor 19, to the main circuit 2 at a side of the interrupter 1 opposite to that to which the conductor 16 is connected to the circuit 2.

The cathode circuit is adapted to receive local current from the main circuit by reason of the drop of potential across the device 17. This local current may be so chosen, or adjusted by the resistor 14, as to render the cathode 13 normally relatively cold or to maintain it at a predetermined relatively high temperature. Whether the cathode 17 shall be maintained at one temperature or another depends upon the characteristics of the circuit 2, and while it is desirable to normally maintain the cathode relatively cool to conserve the life thereof, certain advantages will obtain by normally maintaining it relatively hot. One of these advantages is that it is easier to raise the cathode temperature from a relatively high value that may be, at the same time, just below that required to give the required electron emission, to that at which the main circuit current will freely traverse the valve, than it is to so raise the temperature from a lower value.

In operation, when an overload or short circuit occurs, the interrupter 1 will be actuated by the tripping device 8 to separate the contact members 3 and 4. This action, during which an arc of very short duration may occur, will immediately cause the main circuit current to traverse the parallel path consisting of the conductor 19, the anode 18, the electron-filled space between the anode 18 and the cathode 13, and the conductor 16. The sudden rise of the main circuit current, just previous to the opening of the interrupter 2, will so heat the cathode 13 as to cause the emission of a

sufficient quantity of electrons to convey the shunted current through the valve with substantially no opposition.

When the interrupter 2 opens, the cathode 5 13, being deprived of its source of energy, will quickly, but by graduated amounts, be so cooled as to gradually diminish its electron emission. This action will, thus, automatically build up resistance to the main 10 circuit current until the latter ceases to flow. The reactor 15 is adapted to cause the local cathode current, and therefore the cathode temperature, to lag sufficiently to assure the complete transfer of the line current from 15 the breaker to the valve circuit.

As shown in Fig. 2, the arrangement is substantially the same as that shown in Fig. 1, with the exception that the local cathode circuit may be mechanically interrupted, by 20 a switch 20, at the end of a predetermined interval of time after the opening of the interrupter 1. The switch 20 may comprise a stationary contact member 21 and a pivoted switch arm 22 that is biased toward 25 the closed position, by a spring 23, and is provided with a projection 24 for cooperation with a projection 25 carried by the movable parts of the interrupter 1.

As shown in Fig. 3, a battery 26, that 30 takes the place of the device 17 in the forms shown in Figs. 1 and 2, is provided for energizing the cathode 13. Also, as shown in Fig. 3, the resistor 14 is rendered automatically adjustable by the co-operation of terminal taps 27 thereof with a switch arm 28 that is biased toward one position by a spring 29 and actuated toward another position by an electromagnet 30 having a core member 31 and a coil 32 connected to the 40 circuit 2.

While all of the above shown and described forms of my invention are readily adaptable for either alternating or direct-current circuits, the form shown in Fig. 4 45 is particularly adapted for an alternating-current circuit.

As shown in Fig. 4, the system is substantially a combination of the systems shown in Figs. 1 and 3, it having two of the valves 50 12 each similarly connected on opposite sides of the interrupter 2. Since the valves 12 are asymmetric, the arrangement shown in Fig. 4, will ensure the interruption of the main circuit current in the one or the other 55 of the valves during the first half cycle of the alternating-current wave.

While I have shown and described particular forms of my invention, changes may be effected therein without departing from 60 the spirit and scope thereof, as set forth in the appended claims.

I claim as my invention:—

1. A circuit-interrupting system comprising a circuit, a circuit interrupter, an elec-

tron emission valve connected in shunt to 65 the interrupter and means effective only upon an overload in the circuit for energizing the valve.

2. A circuit-interrupting system comprising a circuit, a circuit interrupter, an electron emission valve connected in shunt to 70 the interrupter and means for energizing and for gradually changing the amount of energization of the valve.

3. A circuit-interrupting system comprising a circuit, a circuit interrupter, an electron emission valve connected in shunt to 75 the interrupter and automatically actuatable means for energizing the valve only upon the occurrence of an abnormal condition in 80 the circuit.

4. A circuit-interrupting system comprising a circuit, a circuit interrupter, an electron emission valve connected in shunt to 85 the interrupter, and automatically actuatable means for energizing and for controlling the amount of energization of the valve.

5. A circuit-interrupting system comprising a circuit, and electron-emitting means 90 connected thereto and adapted to interrupt the circuit at the end of a predetermined interval of time after the occurrence of predetermined conditions therein.

6. A circuit-interrupting system comprising a circuit interrupter, and an electron 95 emission valve adapted to conduct the circuit current after the opening of the interrupter and to interrupt the current at the end of a predetermined time interval.

7. A circuit-interrupting system, comprising a circuit interrupter, and an electric 100 valve connected in shunt to the interrupter and having a cathode circuit connected in parallel with a portion of the circuit at one side of the interrupter.

8. A circuit-interrupting system comprising a circuit interrupter, and an electric 105 valve having a cathode circuit connected in shunt to a portion of the circuit, and an anode circuit that, with the cathode circuit, 110 constitutes a series-parallel shunt circuit, the anode and cathode circuits each being connected at one end to opposite sides of the interrupter.

9. In an electric circuit, the combination 115 with a circuit interrupter, of a hot-cathode valve connected across the interrupter, and means responsive to the circuit conditions for controlling the cathode of the valve.

10. In an electric circuit, the combination 120 with a circuit interrupter, of a hot-cathode valve connected across the interrupter, and means responsive to the circuit conditions for controlling the heating of the cathode 125 of the valve.

11. In an electric circuit, the combination 125 with a circuit interrupter, of a hot-cathode valve connected across the interrupter, and

means responsive to the current traversing the circuit for controlling the heating of the cathode of the valve.

12. A circuit-interrupting system comprising a circuit, an electron-emitting means connected thereto, means governed by predetermined conditions in the circuit for rendering the electron means effective to main-

tain the circuit, and means for controlling the period of time during which the electron means remains effective.

In testimony whereof, I have hereunto subscribed my name this 17th day of November, 1920.

OTTO H. ESCHHOLZ.
